ALBERT B. LEWIS, OF McALESTER, OKLAHOMA.

DOOR LOCKING, OPENING, AND CLOSING MECHANISM.

Application filed March 20, 1928. Serial No. 263,197.

This invention relates to a door locking, opening and closing mechanism, and one object of the invention is to provide a mechanism of this character adapted to be controlled by the wheels of a vehicle and which is applicable to garage, mine and other doors for automatic control of the doors by movements of the vehicle.

Another object of the invention is to provide simple, positive, reliable and inexpensive means whereby garage or other doors may be unlocked and opened and closed and locked without the necessity of a driver or other person descending from a car and manipulating the doors or operating parts.

Still another object of the invention is to provide a door and lock controlling mechanism which comprises a comparatively small number of parts not liable to get out of order and which will not be affected and rendered inoperative by rain, snow or other climatic conditions.

The invention consists of the features of construction, combination and arrangement of parts, hereinafter fully described and claimed, reference being had to the accompanying drawings, in which:—

Figure 1 is a sectional plan view through a portion of the front of a garage, showing the working parts in their normal position or position they occupy when the doors are closed and locked.

Figure 2 is a vertical longitudinal section of the same.

Figure 3 is a vertical transverse section through the garage, looking toward the locked and closed doors.

Figure 4 is a longitudinal section on an enlarged scale through the outside or primary trip mechanism, showing the parts partly moved for an unlocking action.

Figure 5 is a view similar to Figure 4 showing the parts fully moved for a door unlocking and opening action.

Figure 6 is a horizontal section through the front of the garage showing the doors closed and locked.

Figure 7 is a section on line 7—7 of Figure 6.

Figure 8 is a view similar to Figure 7 showing the locking means retracted and one of the doors in open position.

In the accompanying drawings, in which I have disclosed my invention for use in con-

nection with a garage, 1 designates a garage, 55 which generally may be of any suitable type and construction, and which is provided at the front with a doorway 2 adapted to be closed by a pair of outwardly swinging hinge doors 3. The doors 3 are designed to be 60 unlocked and opened and closed and locked by the vehicle operated mechanism embodying my invention, and in practice a suitable auxiliary door (not shown) arranged in one of the side walls or the rear wall of the garage 65 is provided to enable the driver or other person to enter and leave the garage. The garage may be provided with a cemented or other suitably paved floor and runway or approach, a floor 4 and runway 5 being shown in the 70 present instance.

Carried by the doors are keeper members 6 adapted to be engaged by spring actuated latches 7 pivotally mounted on the door frame above the doorway. The latches are coupled 75 by flexible connections 8 to a crank arm 9 on one end of a latch controlling rock shaft 10, the other end of which shaft is provided with a crank arm 11 connected by a rod 12 with a crank 13 mounted on the shaft of a 80 double drum or pulley 14. The shaft of this drum is journaled in suitable bearings arranged upon the floor or in a pit or channel sunk in the floor between the line of the doorway and one of the side walls of the garage, 85 so as to be out of the way of the travel of the vehicle.

Journaled in bearings upon the front of the garage structure above the doorway is a door controlling rock shaft 15 provided with 90 crank arms 16 coupled by links 17 with the respective doors. One end of this shaft is also provided with a crank arm 18 to which is fastened one end of a door opening spring 19, fastened at its opposite end to the front 95 wall of the garage. This spring in practice is of sufficient strength to actuate the rock shaft 15 to swing both doors to open position when said doors are released by the latches 7. The other end of the shaft 15 also carries a crank 100 arm 20 to which is connected one end of a door controlling spring 21, the opposite end of which spring 21 is connected with one end of a cord or cable 22, which is fastened at its opposite end with one of the pulleys or drum sections of the double drum 14. Another cord or cable 23 is fastened at one end to the other pulley or drum section of the double drum 14

and is connected at its opposite end to one end of a rod 23, which rod extends longitudinally toward the rear end of the garage and is coupled at its opposite end to a crank arm 24 of a bail-shaped wheel actuated trip member 25 mounted to rock forwardly and rearwardly in suitable supporting bearings. Between its two limbs the cable 22 passes one or more times, as indicated at 22^a, around one of the pulley or drum sections of the double pulley or drum 14. The trip member 25 is so arranged as to lie in the path of a wheel of the vehicle entering the garage and to be moved rearwardly by contact with the wheel for a door closing action and to be held by wheel pressure to keep the doors closed until it is desired to open them.

Arranged at a point in the approach or doorway a suitable distance in advance of the front of the garage is a second bail-shaped wheel actuated trip member 26, mounted to rock in suitable bearings forwardly and rearwardly with relation to the front of the garage. This trip member 26 has an end portion 27 journaled in the spaced sides of an open stationary frame 28, fixed against movement in any suitable manner. At its inner end this frame 28 is provided with a cross-bar having a guide opening 29. The forward end of a sliding control bar 30 is movable in said opening 29, and at its rear end said bar is provided with a headed stud 31 which engages and is fitted to slide in the slot of a longitudinally slotted motion transmitting and compensating link bar 32, which bar is pivotally connected at its outer or rear end to a crank arm 33 on the end 27 of the trip member 26. The control bar 30 is provided with a recessed portion forming a locking shoulder 37 to engage a latch bar 38 on the frame 28. The link 32 is adapted for engagement with a trip and guide member 39 on the frame whereby its depression for effecting a depression of the bar 30 and an unlatching action thereof is obtained, as hereinafter described. On the trip 26 is a crank arm 40 to which is fastened one end of a spring 41, the other end of which is suitably fixed to the frame 28 or a portion of the runway, said spring acting to permit the trip 26 to be swung outwardly by the wheel of a vehicle leaving the garage and to return it, when released by the wheel, to normal position. The bar 30 is coupled by a connecting rod 41 with a cord or cable 42 which is fastened to the same pulley or drum section of the double drum 14 as the cord or cable 23.

Figures 1, 2, 3, 4 and 7 shows the position of the parts when the doors are locked in closed position by the latches 7, and when the garage is empty, that is, no car is present and acting upon the trip 25 to hold the doors locked. When the garage is vacant and the trip 25 set for action, spring 21 is stressed and placed under tension by the setting of

said trip, and spring 19 is also stressed. When the wheel of a car approaching the garage strikes the trip 26 and swings it downwardly and inwardly, the crank arm 33 slides the bar 32 forwardly at a downward inclination under the guide 39 until said arm 33 begins to exert downward pressure on the outer end of the bar 32, tending to swing said bar vertically on the stud 31, whereby pressure will be produced on the forward end of the bar engaging the guide 39, as a result of which the bar 32 acting as a lever on the stud 31 will force the bar 30 downward, thus throwing its locking shoulder 37 out of engagement with the latch bar 38, leaving said bar 30 free to slide forwardly, in which action stud 31 slides in the slot of bar 32. On the release of bar 30 the spring 41, which holds the spring 21 expanded under tension, contracts and said spring 21 contracts and rotates the drum 14, moving the bar 30 on its releasing motion and at the same time moving crank arm 13 to actuate rod 12 and shaft 10 to retract the latches 7, whereupon the spring 19 will operate to swing the doors 3 open. On the rotation of the drum for the unlocking of the doors trip 25 is moved rearwardly and cable 23 slackened to a certain degree. When the car is driven into the garage and a wheel thereof engages and swings the trip 25 forwardly from the full line position to the dotted line position shown in Figure 2, this slack in cable 23 is taken up and the drum 14 revolved to rotate the drum in the reverse direction to that previously described, whereby the crank arm 13 will be moved to return the latches 7 to locking position, while the rock shaft 15 will be actuated through the connections 22 and 21 to swing the doors back to closed position, in which action the keepers 6 will ride under and be automatically engaged by the latches 7. This condition will endure, the doors being closed and latched, and the trip 26 remaining in thrown position, as long as the car is in the garage with its wheel engaging and holding the trip 25 in its maximum thrown position, in which condition of the parts spring 21 will be held stressed. A slight backward movement of the car, which may be such as to permit the trip 25 to move back a distance of two or three inches, will relax the tension on the spring 21 and cause it to turn the drum sufficiently to operate the rock shaft 10 to retract the latches 7, without causing the doors to open, since the spring 21 will still be tensioned sufficiently to prevent door opening movement of the rock shaft 15 by the spring 19.

A further backward movement of the car, however, to the extent of two or three inches will be sufficient to reduce the tension of the spring 21 so that the spring 19 may be operated to swing the doors open before the trip 25 is fully released by the car wheel. Provision is thus made for a very sensitive

controlling action by the car when in the garage, so that a positive door unlocking action may first be obtained and a door opening action then secured to ensure a full opening 5 movement of the doors within a comparatively small period of time, a factor of importance in preventing possible damage to doors when the garage is small and very little travel of the car is permitted before it reaches 10 the doorway. When the car passes through the doorway and out upon the approach and strikes the trip 26, a wheel of the car engaging the trip will swing it outwardly from the position shown in Figure 5 to that shown in 15 Figures 2 and 4, thus resetting or returning the trip 26 and bar 30 to normal position in which the bar is locked, in which action, through the connections 41 and 42, the drum 14 is revolved to set the latches 7 into locking 20 position and to swing the doors 3 to closed position, in which they will be automatically locked, through the operation of the crank shaft 15 by the connections 21 and 22.

From the foregoing description, taken in 25 connection with the accompanying drawings, my improved door opening, closing and locking and unlocking mechanism will be readily understood, and it will be seen that the invention provides a mechanism of this character 30 which is simple of construction, adapted to be positively operated by the wheels of a vehicle, and which provides for a reliable and secure opening and closing movement of the doors and releasing and locking action 35 of the locking mechanism. The parts of the mechanism, it is obvious, may be arranged wholly at one side of the line of the doorway, so as to be out of the way, with the exception 40 of the trip projections, of the line of travel of the car, allowing free travel of the car without liability of damage to any of the mechanism. The mechanism may be installed in garages of different styles at a comparatively low cost, and, as the parts require 45 no lubrication, maintenance expenses will be reduced to the minimum. While the parts are of such structure that they are not liable to be clogged or damaged by rain, snow, ice or action of the elements, they may be suitably 50 enclosed and protected at comparatively small additional expense.

While the mechanism has been shown as applied, for example, to a garage, it is to be understood that it may be used in conjunction with automatic mine doors or with other doors where it is desirous to employ automatically opening and closing doors operated by the action of a moving vehicle.

Having thus fully described my invention, 60 I claim:—

1. In a door opening, closing and locking mechanism, a door, means for automatically opening the door, a lock for holding the door closed, a wheel operated member, a bar, locking means for said bar, means operable by

the wheel operated member for moving said bar out of and into engagement with the locking means, a transmission member, a connection between the transmission member and the door opening means including a 70 spring tensioned when the wheel operated member is in normal position and the bar is locked to move the transmission member for a door unlocking movement when the wheel operated member is actuated to unlock the 75 bar, and an operating connection between the transmission member and the door lock.

2. In a door opening, closing and locking mechanism, an automatically opening door, a wheel operated member, a transmission member, a door lock projected and retracted by reverse movement of said transmission member, a spring tensioned by a door locking movement of the transmission member for transmitting door unlocking motion to 80 said member, and a connection between the transmission member and the wheel operated member including a latch for holding the transmission member in door locking position, said latch adapted to be released by the 85 wheel operated member to permit the tensioned spring to move the transmission member to door unlocking position.

3. A door opening, closing and locking mechanism, an automatically opening door, 90 a lock for holding the door closed, a tilting wheel operated member, a transmission member coupled to the lock for projecting and retracting the same, a spring adapted to be tensioned by the transmission member when 95 moved to lock projecting position for subsequently returning the same to lock releasing position, a bar coupled to the transmission member for shifting it to lock projecting position and releasing it for movement to lock 100 releasing position, a latch for holding the bar in the first-named position, and a wheel operated member for unlatching and resetting said bar.

4. In a door opening, closing and locking mechanism, a self-opening door, a lock for holding the door closed, a motion transmission member, a controlling connection between the same and the lock, a spring adapted to be tensioned by the transmission member when the latter is moved to lock projecting position for subsequently returning said member to lock releasing position, and wheel controlled means for maintaining the transmission member in lock projecting position 110 and releasing it for movement to lock releasing position by the spring.

5. In a door opening, closing and locking mechanism, a door, a lock for holding the door closed, a rock shaft coupled to the door, a spring acting on said shaft for opening the door when the lock is released, a transmission member, a controlling connection between said member and the lock, a second spring 120 connecting the transmission member with 130

the rock shaft and adapted to be tensioned when said transmission member is in lock projecting position for subsequently returning it to lock retracting position, and wheel controlled means coupled to the transmission member for holding it in lock projecting position and releasing it for lock releasing action by said second spring.

6. In a door opening, closing and locking means, a self-opening door, a lock for holding the door closed, a transmission member coupled to the lock and movable to positions to respectively hold the lock projected and to release the lock, means set for operation on the movement of the transmission device to its first-named position for subsequently moving said device to its second-named position, and wheel controlled means for moving the transmission device to its first-named position and holding it in said position until operated by a wheel and thereupon releasing said transmission device to permit of its movement to lock releasing position by said first-named means.

7. In a door opening, closing and locking mechanism, a self-opening door, a lock for holding the door closed, a transmission member for shifting the lock to projected and retracted positions, means normally operative when the transmission device is in lock projecting position to move it to lock releasing position, a wheel operated member, a bar coupled to said member and operative in one direction to move the transmission device to lock projecting position and when moved in the opposite direction to permit said device to move to lock releasing position, a latch for holding the bar in the first-named position, and connecting means between the wheel operated device and the bar for moving said bar in the direction stated and into and out of engagement with its latch.

8. In a door opening, closing and locking mechanism, a self-opening door, a lock to hold the door closed, a transmission device, means operated thereby for projecting and retracting the lock, a member operatively adjustable by the transmission device in its movement to lock projecting position for subsequently shifting said device to lock releasing position, a sliding and tilting bar coupled to the transmission device and movable in one direction to shift said device positively to lock projecting position and in the reverse direction to permit said transmission device to move to lock releasing position, a latch for holding said bar in the first-named position, a wheel operated member for shifting the bar, a crank actuated by said member, a slotted link coupled to the crank and slidably and pivotally connected with the bar, and a member engageable by the link for effecting a movement to shift the bar out of engagement with its latch.

9. In a door opening, closing and locking

mechanism, a door, a spring for opening the door, a lock for holding the door closed, a transmission member coupled to the lock and movable to lock projecting and releasing positions, a wheel operated member, a second spring adapted to be tensioned when the transmission member is moved to lock projecting position for subsequently shifting the transmission device to lock releasing position, said spring being coupled to the door and operative when fully tensioned to hold the door closed against the resistance of its opening spring after the latch is retracted and during a predetermined movement of said transmission device in latch releasing direction, and a wheel operated member coupled to the transmission device and movable in one direction to shift said device to lock projecting position and in the reverse direction to permit said device to move in lock releasing direction.

10. In a door opening, closing and locking mechanism, a door, a rock shaft coupled to the door, a spring connected to said shaft for forcing the door open, a lock for holding the door closed, a transmission device coupled to the lock and movable in reverse directions for lock projecting and retracting actions, a wheel operated member, a connection between said member and the transmission device operative in one direction of movement of said member to positively shift the transmission device to lock projecting position and on the reverse movement of said member to permit said transmission device to move to lock retracting position, and a connection between the transmission member and rock shaft including a spring adapted to be tensioned by the movement of said device in lock projecting direction to subsequently shift said device in the lock releasing direction.

11. A door opening, closing and locking mechanism comprising a pair of wheel operated members located one on each side of the door, a lock for the door controlled by each wheel operated member, spring actuated means for opening the door when unlocked, a transmission member, connecting means between said transmission member and the lock, connecting means between said transmission member and the door opening means including a spring adapted to be tensioned to hold the unlocked door closed against the action of its opening means, connecting means between one of said wheel operated members and the transmission member including a latch for holding said means in position for holding the lock in lock position, said means being movable in one direction to release the latch and lock and in the reverse direction to close the door and reset the latch and lock, and a connection between the other wheel operated member and the transmission member operative on a movement of said wheel operated member in one

direction to close the doors, set the lock and tension spring in the connection between the transmission member and door opening means so that the resistance of said spring to door opening movement will be greater than the working strength of the spring of the door opening means, said second-named wheel operated member being adapted to be held by

a wheel in thrown position against the resistance of the tensioned spring and movable ¹⁰ reversely under the action of said spring when relieved from wheel pressure to first release the lock and then untension said spring so as to permit the door to open.

In testimony whereof I affix my signature.
ALBERT B. LEWIS.
